HOUSE NUMBER

Walter A. Curtze, Erie, Pa.

Application November 23, 1954, Serial No. 470,672

2 Claims. (Cl. 40—140)

This invention is intended to make a house number 15 in which desired combinations of numerals can be quickly and permanently assembled. The construction comprises a frame having parallel bars held in spaced relation by a ring and having opposed slots open at at least one end and slidably receiving numeral carrying plates. The bars are made of soft malleable material such as aluminum so that when the desired combination of plates is assembled, the plates can be permanently locked in place by peening the lips of the slots against each plate.

In the drawing Fig. 1 is a front view of the house 25 number, Fig. 2 is an end view, Fig. 3 is a perspective from the back, and Fig. 4 is an enlarged section showing how the plates are held in place.

The supporting frame for the house number comprises a ring 1 on the front face of which are two parallel bars 2 extending chordwise across the ring and having opposed slots 3 in the edges of the bars. The slots face each other and slidably receive opposite ends of plates 4 and 5. The plates 4 carry numerals 6 and the plates 5 are blank or filler plates which fill in the space in the frame 30 so the desired numeral combination can be centered in the frame.

2

The bars 2 can conveniently be cast integral with the ring 1 from a malleable metal such as soft aluminum. The slots 3 can be milled in opposed edges 7 of the bars, the slots being slightly wider than thickness of the plates 5 4, 5 so the plates can be easily slid in place.

To lock the plates permanently in place, the assembly is laid face down on a smooth solid surface and the lips 8 of the slots are peened against the plates with a hammer. While the assembly is face down, there is no 10 tendency for the plates to slide and the side edges 9 of the plates can be held tight against each other. The malleable nature of the aluminum makes the peening easy and solidly holds the plates in place. Other malleable metals may be used.

What is claimed as new is:

1. A house number, a frame comprising a ring having on its front face two parallel bars of malleable metal extending chordwise of the ring and rigid therewith, said bars having opposed slots in the opposed edges of the 20 bars and open at at least one end, rectangular numeral carrying plates having opposite ends slidably received in said slots, and one of the lips of the slots being peened against the plates to solidly anchor the plates in place.

2. A house number, a frame comprising a ring having on its front face two parallel bars of malleable metal extending chordwise of the ring and rigid therewith, said bars being cast integral with the ring, said bars having opposed slots in the opposed edges of the bars and open 25 at at least one end, rectangular numeral carrying plates having opposite ends slidably received in said slots, and the back lips of the slots being peened against the back surface of the plates to solidly anchor the plates in place.
